UNITED STATES PATENT OFFICE.

VERN K. BOYNTON, OF NEW YORK, N. Y., ASSIGNOR TO PERRY & WEBSTER, INC., OF NEW YORK, N. Y., A CORPORATION OF NEW YORK.

PROCESS FOR FUME CONTROL.

Application filed May 27, 1921. Serial No. 473,073.

To all whom it may concern:

Be it known that I, VERN K. BOYNTON, a citizen of the United States, residing in New York city, county of New York, borough of Manhattan, and State of New York, have invented certain new and useful Improvements in Processes for Fume Control, of which the following is a full, clear, and exact specification.

10 My invention relates to the control of fumes and devices suitable for the application of my process and refers particularly to the control of fumes arising during the thinning operation of paint vehicles, varnishes and similar materials and apparatus relating thereto.

This application has been divided and divisional application filed in the United States Patent Office on January 23, 1922 20 under Serial Number 531,300.

In the production of paint vehicles, varnishes and similar products, the oleo-resinous compound, or mixture, resulting from the heating of the vegetable oils, gums, resins, &c. is thinned by adding thereto a volatile compound, the nature and character of which depends upon the particular oleo-resinous mixture employed and the final result desired.

30 The heated oleo-resinous mixture is generally removed from the proximity of the fire into a cooling room and the necessary thinners added. These thinners are generally of a highly volatile character and, as they are usually added to the melt while the latter is still at a temperature causing volatilization, fumes of the thinners are given off in copious quantities.

Among the thinners employed are turpentine and benzene and, it is evident that it is 40 economically important that the fumes should not be allowed to escape into the air and thus be lost and, as the fumes combine with air to form mixtures having highly inflammable and explosive properties, it is further highly advisable to so control them as to prevent the formation of such dangerous mixtures.

The usually employed device for the thinning operation of products of the described 50 character comprises the kettle containing the hot melt and a cover for the kettle having an opening connected with a conduit, which conduit is connected with a cooling and con-

densing device for the condensation and collection of the fumes that have escaped from the kettle through the conduit. The passage of the fumes from the kettle and through the conduit may be caused by the vapor pressure of the fumes within the kettle or by an artificially enforced draught.

The process of depending upon the produced vapor pressure as a means for moving the produced fumes is dangerous in its application and unreliable in its results. 65 When the fumes are thus allowed to accumulate within the kettle, they frequently form inflammable and explosive mixtures, thus making the process a dangerous and expensive one. If, as is usual, a number of 70 these fume exit conduits are connected to a manifold, it is impossible to determine the relative quantity of thinner that has condensed and returned to any particular melt and that which has escaped from the kettle, 75 and hence, the amount of thinner remaining in the cooled melt is a varying one, as regards different batches, thus producing varying, un-uniform and un-reliable results.

Previously employed artificially induced draughts have been predicated upon the idea of removing all fumes from the kettle and recovering as much as possible by condensation. This process of operation has many 80 objectionable features. As all batches are 85 not of exactly the same temperature at the time of adding the thinner, varying quantities of thinner are volatilized. There is always an undeterminable amount of thinner 90 condensed within the kettle and returned to the melt, especially as the melt becomes cooler. The operator is compelled to previously calculate the amount of thinner that will escape from the kettle and add that amount in excess in the beginning of his operation so 95 that his finished melt will have the desired quantity and, as the withdrawn quantity of fume can not be accurately measured in advance of the operation, his final product will vary in the different batches, or, he must 100 measure the condensed fumes, if he employs a separate condensing device for each kettle and then add any excess or sufficiency of thinner to the next batch and blend the two batches.

105 Further, in these artificially induced draught devices, no means were employed to control the admixture of air and fumes to

2
prevent the danger and expense incident to the production of inflammable and explosive mixtures.

The process of my invention and the device suitable for its application present a method and means whereby all of the above and other difficulties may be overcome and whereby the thinning operation may be performed easily, economically and safely with the production of uniform and controlled results.

My invention is based upon the principle of so controlling the fumes within the kettle as to return practically all of them in a condensed condition to the melt and to further so control the admixture of air with them as to prevent all possibility of the formation of inflammable and explosive mixture and to reduce to a minimum the amount of fumes incident to the saturation of the admixed air.

It is evident that if practically all of the volatilized thinner be returned to the melt during the thinning operation, the operator can accurately determine the amount of thinner to be added to produce the desired result. It is further evident that it will obviate the necessity of using quantities of thinner largely in excess of that desired in the finished result.

It is further evident that uniform results can be obtained from repeated batches and that these results can be controlled by the initial addition of definite quantities of thinner.

The process of my invention produces all of these desirable results and, therefore, presents a new, valuable and useful method for accomplishing the thinning of the materials mentioned.

I have discovered that if the draught upon the kettle be properly controlled to balance the volume of produced fume, air can be admitted into the kettle below the cover in restricted and controlled quantities and in necessary dilution to avoid explosive mixtures and that the fume will be maintained within the kettle, or adjacent thereto, until practically all of it has reached the condensing point, thereby being returned to the batch and also preventing the escape of any considerable quantity of fume, thus removing the danger of the production of fires or explosions from overflow of fume.

In the accompanying drawings, illustrating one form of a device suitable for the carrying out of my process, similar parts are designated by similar numerals.

Figure 1 is a front plan view of one form of my device partly in section.

Figure 2 is a view through the line 2—2 of Figure 1.

The device of my invention, shown in the accompanying drawings, comprises a kettle 10, around the upper periphery of which is

a series of extended bolts 11, 11. The kettle carries a removable cover 12, having an extended annular flange 13 and a series of flanges 14, 14 upon its inner face. The cover 12 has the thermometer opening 15 and the funnel opening 16, which can be closed by the pivoted covers 17 and 18 respectively. The kettle cover has the operating opening 19, capable of being closed by the hinged door 20. The cover 12 has the fume opening 21. Attached to, and supported by, the cover 12 is a semi-spherical member 22, having an opening 23 corresponding to the fume opening 21 of the cover. Supported by the member 22 and revoluble therein is a hollow spherical member 24, having a lower opening 25 and an upper opening 26 within the flange 27. The two members 22 and 24 thus form a revolvable joint to allow of the positioning of the member 24 in order that the pipe 30 may be attached thereto. Carried by the flange 27 is a pipe 28, within which is a damper 29, the upper extremity of the pipe 28 being connected with a flexible tube, or pipe, 30, which, in turn, is connected with a source of artificial, or natural, draft or suction.

The operation of the device is as follows:

The oleo-resinous mixture and the thinners are added to the kettle 10 through the operating door 20, which is then closed, the openings 15 and 16 being closed. The damper 29 is opened and a draft, or suction, created within the pipe 30, thus having a tendency to draw the fumes upwardly from within the kettle 10. During this operation, air is drawn through the annular opening between the kettle 10 and the cover 12 inwardly into the upper portion of the kettle 10. It is evident that the amount of air thus introduced into the kettle and the amount of air and vapors withdrawn through the pipe 30 can be governed and controlled by the regulation of the damper 29. It is further evident that this introduced air, which is cooler than the evolved fumes, will pass inwardly under the inner face of the cover 12 and outwardly through the opening 21, thus forming what may be called a "blanket" of cooler air above the fumes.

Advantage is taken of these two facts in the application of the process of my invention as follows:

The damper 29 is so positioned that there will be a moving blanket of cooler air in contact with the inner face of the cover, so that practically all of the fumes will be held beneath it and, coming into contact with this cooler blanket, will be condensed and fall back into the contents of the kettle. By this control and regulation of the draft, coupled with the admission of cooler air, it is possible to prevent practically any of the

fumes from escaping from the kettle and its adjacent parts, such as the revoluble joint and the lower portion of the flexible tube.

It is further evident that such a control and regulation will prevent the fumes from flowing over the top of the kettle with the accompanying danger of fire and explosion, and that these dangers are also obviated within the kettle or its adjacent parts.

10 The proper regulation of the damper is readily accomplished by opening the door 18 and observing the operations within the kettle. If fumes are observed escaping through the opening 16, it is evident that the 15 damper should be opened somewhat, in order to admit more air and form a thicker blanket. The appearance of the vapors beneath the air blanket clearly demonstrates whether the damper should be opened or closed, thus 20 presenting an easily demonstratable determination of the control and regulation to be employed.

By "kettle" in my specification and claims, I mean any receptacle, or container, suitable 25 for the carrying out of my process.

I do not limit myself to the particular size, shape, number or arrangement of parts as shown and described, nor to the particular means or steps of process as described, all of 30 which may be varied without going beyond the scope of my invention as shown, described and claimed.

What I claim is:—

1. A process for controlling fumes within 35 a covered kettle which comprises admitting air into the upper portion of the kettle, inducing a draft to the upper portion of the kettle and controlling the amount of draft whereby the amount of air drawn into the 40 kettle will be controlled.

2. A process for controlling fumes within 45 a covered kettle which comprises admitting air into the upper portion of the kettle, inducing and controlling a draft in the upper portion of the kettle so that approximately all of the condensable fumes will be condensed within the kettle and its adjacent parts.

3. A process for controlling fumes within a covered kettle which comprises admitting 50 air into the upper portion of the kettle, inducing a draft to the upper portion of the kettle and controlling the amount of draft whereby a moving blanket of admitted air will be formed adjacent to the inner face of 55 the cover.

4. A process for controlling fumes within a covered kettle which comprises admitting air into the upper portion of the kettle, inducing a draft to the upper portion of the 60 kettle and controlling the amount of draft whereby the air drawn into the kettle will retain approximately all of the condensable fumes within the kettle and its adjacent parts until approximately all of the condensable fumes have been condensed.

5. A process for recovering fumes evolved in the thinning process of paint vehicles, varnishes and similar materials which comprises adding volatile thinners to a heated 70 mixture of oleo-resinous materials within a covered kettle, admitting air into the upper portion of the kettle, inducing a draft to the upper portion of the kettle and controlling the amount of draft whereby the admitted air will retain approximately all of the volatilized thinners within the kettle and its adjacent parts until they have been condensed and returned to the oleo-resinous materials.

6. A process for recovering fumes evolved in the thinning process of paint vehicles, varnishes and similar materials which comprises adding volatile thinners to a heated 85 mixture of oleo-resinous materials within a covered kettle, admitting air into the upper portion of the kettle, inducing a draft to the upper portion of the kettle and controlling the amount of draft whereby the admitted air will retain and condense approximately all of the volatilized thinners within 90 the kettle and its adjacent parts.

Signed at New York in the county of New York and State of New York this 26th day of May, 1921.

VERN K. BOYNTON.
